UNITED STATES PATENT OFFICE.

SOLOMON R. WAGG, OF APPLETON, WISCONSIN; JAMES B. WAGG ADMINISTRATOR OF
SAID SOLOMON R. WAGG, DECEASED.

APPARATUS FOR TREATING PAPER.

1,208,415.

Specification of Letters Patent.

Patented Dec. 12, 1916.

Application filed October 12, 1915. Serial No. 55,550.

To all whom it may concern:

Be it known that I, SOLOMON R. WAGG, a citizen of the United States, residing at Appleton, in the county of Outagamie and State of Wisconsin, have invented new and useful Improvements in Apparatus for Treating Paper, of which the following is a specification.

The present invention pertains to a method and apparatus for treating paper, and more especially of paper in the form of continuous strips or webs, and comprehends improvements over the method and apparatus for treating paper as disclosed in my prior Patents Nos. 1,117,113 and 1,117,114.

The objects aimed at by the present invention are to reduce the size of the machine, and decrease the number of its parts, with a resultant decrease in the cost of construction of the machine; and to provide an apparatus or machine which will require less floor space and care, and which will produce a wet web of paper free of spots and specks of dirt which have heretofore been occasioned on the wet web due to the latter passing through an extended machine and over a substantially dry winding drum upon which dirt accumulates and peels off and sticks to the wet web before the latter is wound into a roll.

It is also an object of this invention to produce an apparatus or machine as above described that will prevent air blisters and wrinkles upon the web of paper under treatment.

With the above ends in view, the invention contemplates a sizing tank over which are mounted the superposed expressing rollers and an adjustable support for the reel on which the web is wound up, the surface of the reeled up web contacting with the periphery of one of said expressing rollers, the movement of which latter effects the winding of said web upon the reel.

It is also a feature of the invention to provide a pair of spaced rollers mounted directly over the upper expressing roller for guiding the web from the latter to the reel, and to also provide a spreader roll disposed between said guide rollers.

With the above ends in view, the invention consists in a certain novel construction, combination and arrangement of parts hereinafter more fully described and finally pointed out in the appended claims.

In the drawings which form part of the specification: Figure 1 is a side sectional view of the apparatus contemplated by the invention; and Fig. 2 is a top plan view of said apparatus.

The new and improved treatment, like the earlier treatments above-mentioned, may be carried out with or by the aid of any suitable apparatus, an embodiment of that preferred being shown in the accompanying drawings.

In the drawings, 1 indicates the strip or web of paper undergoing treatment and 2 the bath of gelatin or other sizing medium through which the same is passed by immersion as the initial step of such treatment. This web of paper may or may not have been subjected to the usual preliminary engine sizing, with or without mordants, and may be led to the bath for immersion directly from the machine, or after it has first been reeled up in a dry state. On leaving the size bath, the immersed wet paper web passes between the rolls 3 and 4 which serve to remove and express the excess size from the web, and from these rolls it is wound, while still in a wet state, directly upon the winding reel 5 supported upon the adjustable arms 6, as clearly shown in Fig. 1 of the drawings. The adjustable arms 6 have one end pivotally secured to the axis of the roll 4, as shown at 7, and are held in an inclined position by the connected links 8 and 9 which are adjusted by the mechanism 10.

The arms 6 and their supporting and adjusting mechanism are preferably of the type shown and described in the aforesaid patents and are designed for supporting the reel of paper in frictional contact with the winding drum. In the present instance, the arms 6 are adapted to adjustably support the reel 5 and permit the same to gravitate in frictional contact with the peripheral surface of the roll 4 at a point above the axis thereof. It will thus be seen that the roll 4 performs a dual function, that is, by coöoperating with the roll 3, on its lower side, to express excess size from the web 2 and to act as a winding drum contacting with the reel 5 for winding the web upon the latter.

Any suitable driving mechanism may be connected with the sizing rolls 3 and 4, and the latter are disposed directly over the size bath 2 so that the expressed size may drip back into the bath. It is contemplated by

the invention to pass the web over a spreader roll after the web has passed through the size expressing rolls and before the same is wound upon the reel 5. For carrying out this purpose, it is preferred to pass the web over spaced guide rolls 11 and 12 immediately before the same is wound upon the reel. Interposed between said guide rolls is the spreader roll 13 yieldably mounted so as to be sensitive to the varying thicknesses of the sized web.

With the method and apparatus above set forth, it will be obvious that the sized web will be produced free from spots and specks of dirt which occur on the web when the same is passed through an extended machine and when the reel is wound from a substantially dry winding drum, since the size from the web accumulates on the surface of the drum, hardens, peels off, and is finally deposited upon the web, causing considerable waste of the latter. In the present instance, the reel is wound directly from one of the sizing rolls itself, which latter is constantly wet with the excess sizing being squeezed from the web which consequently eliminates the possibility of such hardened extraneous substances, formed on the surface of the drum, being deposited on the web as the same is being wound, as is the case with the dry winding drums now in use. Also, in view of the simplified construction of the apparatus, the web does not pass over or between a multiplicity of rolls and other elements, so that it is not exposed to the foreign substances in the atmosphere which are frequently deposited thereupon.

According to the construction shown in the drawings, the rolls 4 and 5 are superposed and rotatably mounted in the uprights 14 secured on opposite sides of the tank 2, the lower roll 3 being of less diameter than the upper roll 4. The upper ends of the uprights 14 are provided with the substantially horizontal extensions 15 which are slightly inclined, as shown in Fig. 1. The extensions 15 extend from said uprights in a direction away from the reel 5 and have journaled at their opposite ends the guide rollers 11 and 12, respectively, which extend transversely of the tank 2 and are parallel with the rollers 3 and 4 and the reel 5. The spreader roller 13 extends substantially parallel with the rollers 11 and 12 and is yieldingly mounted therebetween, by means of a spring 16, in brackets 17 secured to the extensions 15. A doctor or scraper blade 18 is secured on extensions 17 projecting

from the uprights 14 and engages with the roller 4 under the reel 5 for cleaning the surface of said roller.

From the foregoing, it is believed that a clear understanding of the present invention may be had. However, it is to be understood that certain changes as to the precise construction, combination and arrangement of parts may be resorted to that fall within the legitimate scope of the appended claims.

What is claimed is:

1. An apparatus for treating paper web, comprising, a size bath through which said web is passed, size-expressing rolls disposed over said bath and between which said web is passed and fed forward, and a reel on which the web is wound up, said reel supported to hold the web thereon in frictional contact with one of said rolls so as to cause the rotation of said reel therefrom. 70

2. An apparatus for treating paper web, comprising, a size bath through which said web is passed, size-expressing rolls disposed over said bath and between which said web is passed and fed forward, a winding reel for the web, and an adjustable support whereon said reel is carried to be gravitally held in frictional contact with one of the said rolls whereby said web is wound and the reel operated from said roll. 80

3. An apparatus for treating paper web, comprising, a size bath, size-expressing rolls disposed over the bath and feeding said web forward, a winding reel for the web in frictional contact with one of the rolls and to be operated thereby, and a spreader roller over which said web is passed after the size has been expressed therefrom and before being wound upon said reel. 90

4. An apparatus for treating paper web, comprising, a size bath, size-expressing rolls disposed over the bath and feeding said web forward, a winding reel for the web and in frictional contact with one of the rolls to be operated thereby, spaced guide rolls, and a yielding spreader roller disposed between said guide rolls, said web being passed over 100 said guide rolls and spreader roller after the size has been expressed therefrom and before being wound upon said reel. 105

In testimony whereof I have hereunto set my hand in presence of subscribing witnesses. 110
